UNITED STATES PATENT OFFICE.

EDWARD RAYMOND-BARKER, OF WIMBLEDON, ENGLAND, ASSIGNOR TO THE AMALGAMATED RADIO-TELEGRAPH COMPANY, LIMITED, OF LONDON, ENGLAND.

RADIOTELEGRAPHY.

1,139,226.

Specification of Letters Patent.

Patented May 11, 1915.

Application filed January 9, 1908. Serial No. 410,014.

To all whom it may concern:

Be it known that I, EDWARD RAYMOND-BARKER, a subject of the King of Great Britain, residing at 12 Edge Hill, Wimbleton, in the county of Surrey, England, have invented certain new and useful Improvements in or Relating to Radiotelegraphy, of which the following is a specification.

This invention relates to radio-telegraphy, its object being the provision of a system in which the signals instead of being made up of long and short elements as is usual in wireless systems, are composed of approximate equal-time-value-elements.

According to this invention the signals are produced by waves of different lengths, the transmitting apparatus being arranged to transmit oscillations of two or more different wave-lengths and the receiving station correspondingly adapted to receive the same. The system according to this invention is particularly suitable for use in connection with receiving apparatus of the kind in which a telephone is used, and when so employed may be regarded as a two- or multi-tone radio-telegraphic system.

It is to be understood that the improved system, depending as it does upon the possibility of transmitting signals of definite wave-lengths, is primarily intended for use in connection with radio-telegraphic apparatus of the kind in which fine tuning is practically possible. Various systems have been suggested, but for the purpose of the following description the Poulsen system is referred to as typical of one capable of fine selective tuning. As is well known, in the Poulsen system the oscillations are produced in a circuit containing properly adjusted capacity and self-induction shunted across the main circuit containing an arc.

The invention may be regarded as the application to a radio-telegraphic system in which fine selective tuning is possible of the equal-time-element system of working as opposed to the Morse system of short dots and long dashes.

The equal-time-element-system is in principle well known as applied to ordinary telegraphy, as for example, in the single needle sounder, Bright's bell apparatus, the Kelvin siphon recorder, and in M. Ader's photographic receiver, and the advantages gained over the Morse long dash and short dot system in ordinary telegraphy are, by

this invention, gained for wireless work, with the added advantage of increased secrecy of working.

Various electrical arrangements may be made for carrying out the invention, and in the accompanying drawings:—

Figures 1, 2, 3 and 4 illustrate, by way of example, various systems of connections for transmitting signals formed of elements of different wave-lengths. Figs. 5 and 6 show two systems of connections for receiving apparatus, and Figs. 7 and 8 are diagrams illustrating additional recording apparatus which may be used in conjunction with the receiving apparatus shown in Fig. 6.

In each of the examples of transmitting systems shown in Figs. 1, 2 and 3, the power is derived from one or more arcs provided with properly adjusted inductances and capacities so that oscillations of different wave-lengths may be emitted.

With reference first to Fig. 1, this shows a system in which the signals may be sent directly from manually operated dot and dash keys A and A¹. The connections are based on one of the Poulsen systems, and an antenna B is joined through an inductance C and capacity D to one terminal E of an arc F. In this particular arrangement two arcs are provided each fed from a generator circuit G and each having a capacity D and inductance C in circuit with it. But the adjustment of these inductances and capacities is such that the wave emitted from the antenna B when placed in circuit, say by the key A, with one arc, is of greater length than the wave correspondingly emitted from the other circuit when the key A¹ is employed.

The keys are shown in their normal or resting positions, and it will be seen that a back contact H is furnished in each case, this back contact being in connection with an inductance C¹ and capacity D¹ forming an oscillatory circuit of feeble emissive power, but of the same period and damping rate as the antenna system. This second circuit is thrown into the arc circuit when the antenna is cut out by releasing the key.

The connections shown in Fig. 2 illustrate by way of example the employment of one arc instead of two, and also show how the signaling can be accomplished manually from a simple form of sending key through the operation of electro-magnetic devices.

A² is the double sending key controlling a battery J and local circuits a and b. In the local circuit a is an electro-magnet K, while a similar electro-magnet K¹ is placed 5 in the local circuit b. The armature lever K² of each of these electro-magnets controls three contacts k¹ k² k³ working in conjunction with a corresponding set of contact-springs k⁴ k⁵ k⁶ k⁷ k⁸ k⁹.

10 The arch F¹ is supplied with current from generator mains G. If now the right hand key is depressed, the electro-magnet K is energized and pulls its armature down, raising all the top contacts k¹ k² k³ into connection with the springs k⁴ k⁵ k⁶ respectively. This throws into circuit with the antenna B the capacity D² through the contact k⁴, the whole of the inductance C² through the contact k⁵ and also places the inductance C³ 15 into the generator circuit through the contact k⁶. If the left sending key A² be depressed, the electro-magnet K¹ operates and throws into circuit, through the contacts k¹ k² k³ operated by it, another capacity D³ 20 and a portion only of the inductance C², for it will be seen that the top contact spring k⁵, instead of being in communication with the end of the inductance C² as is the corresponding contact-spring k⁵ of the right hand 25 side of the diagram, is connected through conductor c to a point about midway of that inductance. This is a convenient arrangement for obtaining from one arc waves of two different lengths to be used as approximately equal-time-value elements in a wireless signal. It will be appreciated that the bottom contacts k⁸ and k⁹ whereon the contacts k² k³ come to rest may throw into the 30 arc circuit supplementary oscillatory circuits of feeble emissive powers for the same purpose as in the arrangement shown in Fig. 1.

C^{2x} and D^{2x} represent inductance and capacity, respectively, of appropriate value 45 in a circuit shunted with respect to the arc and thrown into circuit when the contacts k² k³ of the right hand lever rest upon the contacts k⁸ k⁹. Similarly C^{3x} and D^{3x} represent inductance and capacity, respectively, 50 shunted with respect to the arc and thrown into circuit when the corresponding contacts k² k³ of the left hand lever rest upon the contacts k⁸ k⁹. The contacts k⁷ serve merely as back stops for the contacts k¹.

55 The connections shown in Fig. 3 illustrate by way of example one way in which automatic transmission may be applied to a wireless system giving signals composed of waves of two different lengths, and also 60 shows the use of the method suggested by Poulsen in which there is provided in the generator circuit G or in the antenna circuit, a non-inductive resistance M large enough to keep down the oscillations, signals being sent by short-circuiting this re-

sistance. In this figure L indicates diagrammatically a perforated strip upon which the signals are punched in the well known way, the perforations working in conjunction with flexible brushes L¹ L² after 70 the manner of a Delany automatic transmitter. For the purpose of illustration a double sending key A³ is also shown, and it will be seen that either the strip L or the key A³ can operate local circuits containing 75 electro-magnets K and K¹ controlling radio-telegraphic sending circuits. Two arcs F² are employed each provided with inductances C⁴ and capacities D⁴, the inductances C⁵ and non-inductive resistances M being 80 provided in the generating circuit. It will be seen that the antenna B in this case is always in connection with each of the oscillatory circuits plus the large non-inductive resistances M, and that the action of the 85 electro-magnets K and K¹ is to cut out one or other of those non-inductive resistances so that an undamped oscillation will be emitted from that particular oscillatory circuit. It will be seen that the two contacts 90 k¹⁰ k¹¹ of each electro-magnet K and K¹ control short-circuiting connections e to the respective non-inductive resistances M.

Fig. 4 merely illustrates how by providing supplementary contacts k¹² k¹³ on the armatures of the electromagnets K K¹, the siphon recorder diagrammatically illustrated at N may, through a local circuit and batteries N¹, be made to give a record of all outgoing signals. The receiving apparatus 100 does not need detailed description. The connections must comprise essentially two sets of apparatus, one capable of receiving oscillations of one wave-length and the other oscillations of another wave-length, the inductances and capacities of the two circuits being so adjusted that they are tuned to the wave-length of the oscillation emitted by the particular sending station. In the example 105 of receiving connections shown in Fig. 5 the receiving antenna B¹ is joined to earth through four circuits in parallel with each other, two of these circuits containing inductances C⁶ and the other two capacities D⁶. Each of the inductances C⁶ acts inductively upon another circuit, the inductance C⁶ and capacity D⁶ of which are so adjusted 110 relatively to the main receiving circuit that waves of a certain length reaching the antenna B¹ are rendered audible in a telephone P through the action of a suitable 115 interrupting device such as the ticker P¹.

Fig. 6 illustrates another system of connections for a receiving station adapted in this instance to give visible signals on a 120 siphon recorder instead of audible signals in a telephone. The circuits from the receiving antenna B¹ to earth may be as described with reference to Fig. 5, but in the secondary 125 circuits a wave-indicator or coherer T 130

is provided having a tongue T^1 kept in rapid vibration and acting as an interrupter so as to make intermittent connection between contacts t and t^1 . Another vibrating tongue or interrupter T^2 works in conjunction with a contact t^2 and between the contact t and t^2 is a local circuit comprising a local battery J^1 and a highly sensitive relay U preferably of the suspended-coil type. In this arrangement the vibrations from the primary coil C^6 induce oscillations in the secondary coil C^6 and the vibrating tongues or interrupters T^1 , T^2 are moved synchronously. For instance, they may be mounted mechanically together, say, on the end of one arm of a vibrating lever so that the two gaps in the local circuit containing the relay U and the battery J^1 are closed simultaneously. The sensitive relays U will thus respond to oscillations received by the antenna B^1 if such oscillations be of the proper wave-length to which the receiving apparatus is tuned. The response of each relay U may be utilized in various ways to bring about a visible record of the received signals, and Figs. 7 and 8 illustrate two convenient methods.

In Fig. 7 the two sensitive relays U are shown connected by a double or split battery J^2 , their outer terminals being connected by a conductor f . To the middle point J^3 of the battery J^2 is connected one pole of a sensitive polarized relay V , the other pole being joined to the conductor f . The stationary contacts V^1 and V^2 of this polarized relay are joined to a local battery J^4 , and from the middle point of such battery a conductor g leads to a siphon recorder N^1 . The other pole of this recorder is connected by a conductor h to the movable contact V^3 of the polarized relay. In this system of connections it is only necessary for the sensitive relays U to have one fixed contact U^1 working in conjunction with the moving contact U^2 . From the diagram it will be readily seen that according to which of the sensitive relays U is energized so will the movable contact V^3 of the polarized relay V make connection with either the fixed contact V^1 or V^2 . This polarized relay in fact acts as a battery-receiving key and governs the direction of the current from the local battery J^4 through the recorder N^1 ; thus, a signal record of the ordinary kind will be produced upon the tape. The sensitive relays U are shown as provided with condensers U^4 across their contacts for lessening the sparking at the contact.

Fig. 8 shows another system of connections for bringing about the same result. In this case the sensitive relays U are provided with two fixed contacts U^1 and U^3 working in conjunction with the movable contact U^2 . With this arrangement it will be seen that the battery J^6 need not be

divided, for the sensitive relays U in this case act as double-current or reversing keys and determine which pole of the single battery J^5 shall be connected to any one pole of the polarized relay V . This polarized relay is provided with a high resistance shunt V^4 to prevent sparking at the contacts of the sensitive relays U , U . The connections between this polarized relay V and the siphon recorder N^1 are substantially the same as described with reference to Fig. 7.

The above described transmitting and receiving systems and connections are given as examples showing how signals composed of two different wave-lengths can be transmitted and received by radio-telegraphy either audibly as a two-tone message on a receiver or visibly as on a siphon recorder-tape. Obviously, however, the invention may be carried out in other ways which are in themselves well known methods in ordinary telegraphic work, the essential features being the provision of transmitting apparatus giving waves of two or more different lengths and of receiving apparatus capable of receiving such waves and transmitting them into signals of preferably equal-time-value elements. Given such essentials, other well known telegraphic operations may be carried out besides those already mentioned, such, for example, as the automatic relaying of messages from one long distance circuit to another, or the automatic perforation of messages on a strip of paper to be used for re-transmission. It will, of course, be understood that the term "equal-time-value-element" as used in this specification is intended to distinguish between what is commonly regarded as a recorder or some like signal, and the long dash short dot Morse code. It does not necessarily follow that the signals formed by the oscillations of different wave-lengths would be in themselves equal, although they would probably be approximately equal. But in any case the difference in the time-value of the two signals would not be used for the purposes of distinguishing between a dot and a dash.

One of the principal advantages of the two-tone or two wave-length equal-time-value-system of radio-telegraphy is the great economy of time in signaling, an equal-time-value signal being on the average nearly 30% less than the ordinary long and short Morse signal.

Another advantage is that when acoustic signals are used a two-tone code is much more easily read than is the one-tone long and short code. This advantage is especially marked in the case of bad transmission where the time-value relationship between the dot and the dash is not adhered to; obviously in two-tone signaling, however fast the transmission, the contrast

between the dot and dash is independent of the operator.

What I claim and desire to secure by Letters Patent of the United States is:—

- 5 1. In radio-telegraphy, the combination with an elevated conductor system, electric arcing means, a pair of arc-shunting circuits containing capacity and inductance adjusted to produce undamped electrical oscillations 10 of a known wave length, one of said shunt circuits being associated with the elevated conductor system, another pair of arc-shunting circuits adjusted to produce undamped electrical oscillations of a different wave 15 length, one of said circuits being associated with the elevated conductor system, means for normally keeping the electric arcing means in connection with the arc-shunting circuits that are unassociated with the elevated conductor system and means for breaking the aforesaid connections and making connections between the arcing means and the arc-shunting circuits that are associated with the elevated conductor system 20 in a predetermined order and for equal intervals of time so that the elevated conductor system emits signals composed of elements equal in time value but differing in wave-length.
- 25 2. In radio-telegraphy, the combination with an elevated conductor system, electric arcing means, a pair of arc-shunting circuits containing capacity and inductance adjusted to produce undamped electrical oscillations 30 of a known wave length, one of said shunt circuits being associated with the elevated conductor system, another pair of arc-shunting circuits adjusted to produce undamped electrical oscillations of a different wave 35 length, one of said circuits being associated with the elevated conductor system, means for normally keeping the electric arcing means in connection with the arc-shunting circuits that are unassociated with the elevated conductor system and means for recording the order in which the oscillation producing systems render the 40 elevated conductor system emissive.

elevated conductor system, electromagnetic devices for actuating the aforesaid connecting means to break the aforesaid connections and to make connections between the arcing means and the arc-shunting circuits that are associated with the elevated conductor system, and means for actuating the said electromagnetic devices for equal intervals of time and in a predetermined order.

3. In radio-telegraphy, the combination with an elevated conductor system, electric arcing means, a pair of arc-shunting circuits containing capacity and inductance adjusted to produce undamped electrical oscillations of a known wave length, one of said shunt circuits being associated with the elevated conductor system, another pair of arc-shunting circuits adjusted to produce undamped electrical oscillations of a different wave length, one of said circuits being associated with the elevated conductor system, means for normally keeping the electric arcing means in connection with the arc-shunting circuits that are unassociated with the elevated conductor system, means for breaking the aforesaid connections and making connections between the arcing means and the arc-shunting circuits that are associated with the elevated conductor system in a predetermined order and for equal intervals of 75 time so that the elevated conductor system emits signals composed of elements equal in time value but differing in wave-length, and means for recording the order in which the oscillation producing systems render the 80 elevated conductor system emissive.

In testimony whereof I affix my signature in presence of two witnesses.

EDWARD RAYMOND-BARKER.
